UNITED STATES PATENT OFFICE

2,431,693

STORAGE TANK

George T. Horton, Chicago, Ill., assignor to Chicago Bridge & Iron Company, a corporation of Illinois

Application February 9, 1944, Serial No. 521,599

10 Claims. (Cl. 220—71)

1

This invention relates to a storage tank and more particularly to a generally cylindrical storage vessel which is peripherally formed from a plurality of courses of metal sheets joined at their adjacent edges, and in which at least some of the courses and particularly the lower courses are made up of a plurality of conical segments intersecting with adjacent conical segments on a predetermined surface of revolution about the vertical axis of the tank.

In storage vessels of this form I have found it desirable to transmit the radially outward horizontal components of the scallop stresses to the roof or bottom of the vessel, and, in the embodiment of the invention here described, this is accomplished by connecting roof supporting posts with the intersections of the scallops. This may be accomplished in a number of ways and is illustrated in two forms. In one form the scallop intersection is connected to the top of the post by a tie rod and to the bottom of the post by another tie rod. In the second form the scallop intersection is provided with a partial radial diaphragm connecting it with the bottom of the vessel and with the bottom of the post, and the top of the post is connected to the diaphragm by a tie member.

In this manner the horizontal components of the tie stresses are transmitted to the roof and bottom and the column withstands the vertical components of the tie stresses.

The invention is illustrated in the drawings, in which Figure 1 is a plan view without the roof, partially in section, of one form of the invention; Figure 2 is a partial sectional elevation corresponding to Figure 1; Figure 3 is a plan view without the roof, partially in section, of another modification of the invention; and Figure 4 is a partial sectional elevation corresponding to Figure 3.

Each of the storage vessels shown in the drawings is in general cylindrically formed and the lower portion is made up of scallops, the radius of curvature of which progressively changes.

In Figures 1 and 2 the storage vessel 10 comprises a top 11, a bottom 12, and side walls 13. Roof supporting posts 14 and 15 are provided at suitably spaced intervals. Posts 15 are spaced radially inwardly from the intersection 17 of the scallops 16 and the posts are firmly secured to the bottom 12 at the point 18 and to the top 11 at the point 19.

The side walls of the vessel are made up of a plurality of courses 20 formed from sheets of metal secured to each other at their adjacent

2

edges. The upper courses are circular in outline but the courses below the point 21 are formed of scallops 16 intersecting vertically along the lines 17, 17a, 17b, etc., and of downwardly diminishing radius of curvature.

The points of revolution determining the scallops are so selected that the lines of intersection are essentially vertical in both projections, which results in having the outermost portion of the scallop form the outward bulge 22, shown in Figure 2. This contrasts with the form shown in Figure 4 in which the lines of vertical intersection are vertical only in one projection, whereas the outer line of the scallops is vertical.

15 A triangular girder 23 is welded or otherwise secured to the intersection 17 to provide a suitable means of securing the tie members. The tie members comprise the tie rod 24 which is secured to the top 19 of the post 15 and to the girder 23, and the tie rod 25 which is similarly secured to the bottom 18 of the post 15 and to the girder 23. As shown, the tie rods are joined to the girder almost immediately adjacent each other, but this is not essential. The sketch shows 20 the ties as meeting at a distance $\frac{1}{2}h$ above the tank bottom at which elevation is the centroid of the radially outward horizontal components of the scallop stresses. This has certain advantages but separation of the points of attachment 25 of the ties to the girder may be advantageous in some cases because it reduces the maximum bending moment in the girder.

It is of course understood that the ties are secured directly or indirectly to the roof and bottom, respectively, sufficiently to transmit the horizontal components of the tie stresses thereto.

The posts 15 are of course adapted to withstand the additional vertical stresses imparted by the tie members.

40 In Figures 3 and 4 the storage vessel 110 comprises a roof 111, a bottom 112, side walls 113, and roof supporting posts 114 and 115. The lower portion of the side walls is made up of the scallops 116, the radius of curvature of which decreases downwardly from the point 121 and the center of curvature of which is progressively moved to provide the inwardly sloping lines of intersection 117. The posts 115 are joined at the bottom 118 to the bottom of the tank, and at the top 119 to the top of the tank. A tie rod 124 is secured at one end to the top 119 of the post 115, and at the other to the tie plate 125. This tie plate, which is generally triangular in form, at one edge is secured to the line of intersection 50 117. The bottom edge of the tie plate is secured 55 117.

to the bottom of the tank, and the projection 126 of the third side of the triangle is welded to the post 115.

It will be noted that in the form shown in Figures 1 and 2, the scallops intersect essentially at the periphery of a circular cylinder, whereas in the form shown in Figures 3 and 4 the scallops intersect essentially on the periphery of a circular cone. The deviation from a cylinder is, however, very slight and the vessel is still essentially cylindrical.

The foregoing detailed description is given for clearness of understanding only, and no unnecessary limitations should be understood therefrom.

What I claim as new and desire to secure by Letters Patent is:

1. In a generally cylindrical storage vessel having top, bottom, and side walls, and in which a lower portion of the side walls is formed of a ring of intersecting scallops and in which the upper portion of the side walls is circular in horizontal cross-section, a plurality of posts connecting the top and bottom of the vessel, and tie members connecting each scallop intersection intermediate of its ends with the top and bottom, respectively, of one of said posts, one of said tie members being also secured to the roof of the vessel and the other to the bottom of the vessel, whereby radial horizontal components of the scallop stresses are transmitted to the bottom and top of the vessel and vertical components of the stresses in the tie members are transmitted to the post.

2. A storage vessel as set forth in claim 1, in which both of the tie members are tie rods.

3. A storage vessel as set forth in claim 1, in which the tie member between the scallop intersection and top of the post is a tie rod.

4. A storage vessel as set forth in claim 1, in which the tie member between the scallop intersection and top of the post is a tie rod, and the tie member to the bottom of the post is a diaphragm interconnecting the post, the scallop intersection, and the bottom of the vessel.

5. In a generally cylindrical storage vessel having top, bottom, and side walls, and in which a lower portion of the side walls is formed of a ring of intersecting scallops and in which the upper portion of the side walls is circular in horizontal cross-section, a plurality of posts connecting the top and bottom of the vessel, a vertical girder secured to each scallop intersection and to the bottom of the vessel, a tie rod connecting the top of the vessel and the top of a post to each of said girders, and a tie rod connecting the bottom of the vessel and the bottom of a post to each of said girders, said tie rods substantially meeting at a point above the bottom which is approximately one-third the height of the girders.

6. In a generally cylindrical sheet metal storage vessel comprising a bottom, a top, and side walls connecting said top and bottom, with said side

walls having their lower portions formed of a ring of intersecting scallops that are concave on their inner surfaces, a plurality of posts extending between the top and bottom of the vessel and spaced inwardly from the side walls, and tie members connecting each intersection of adjacent scallops intermediate the ends of said intersection with the top and the bottom, respectively, of one of said posts, with at least the top tie member being a substantially straight tie-rod arranged at an angle with respect to the horizontal.

7. The storage vessel of claim 6 wherein each tie member is a substantially straight tie rod arranged at an angle to the horizontal.

8. The storage vessel of claim 6 wherein the top tie member is a tie rod and the bottom tie member is a diaphragm interconnecting the post, the scallop intersection, and the bottom of the vessel, and the tie rod is fastened to said diaphragm.

9. In a generally cylindrical sheet metal storage vessel comprising a bottom, a top, and side walls connecting said top and bottom, with said side walls having their lower portions formed of a ring of intersecting scallops that are concave on their inner surfaces, a plurality of posts extending between the top and bottom of the vessel and spaced inwardly from the side walls, a vertical radial girder attached to each scallop intersection and to the bottom of the vessel, a tie rod connecting the top of the vessel and the top of a post to each of said girders, and a tie rod connecting the bottom of the vessel and the bottom of a post to each of said girders, said tie rods being attached to the girder intermediate the ends of the girder and being arranged at an angle with respect to the horizontal.

10. The vessel of claim 9 wherein the tie rods are attached to the girder at substantially a common point.

GEORGE T. HORTON.
